US0D1054438S

(12) **United States Design Patent** (10) **Patent No.:** **US D1,054,438 S**
(45) **Date of Patent:** **** Dec. 17, 2024**

(54) **DISPLAY SCREEN WITH GRAPHICAL USER INTERFACE**

(71) Applicant: **Airbnb, Inc.**, San Francisco, CA (US)

(72) Inventors: **Michelle Mederos**, San Francisco, CA (US); **Madelyn Taylor**, San Francisco, CA (US); **Tali Flash**, San Francisco, CA (US); **Christina Nee**, San Francisco, CA (US); **Joy Zhang**, San Francisco, CA (US); **Mia Zhao**, San Francisco, CA (US); **Ying Lyu**, San Francisco, CA (US); **Zach Barbitta**, San Francisco, CA (US); **Jack Fu**, San Francisco, CA (US); **Andy Yasutake**, San Francisco, CA (US); **Yinglu Shao**, San Francisco, CA (US)

(73) Assignee: **Airbnb, Inc.**, San Francisco, CA (US)

(**) Term: **15 Years**

(21) Appl. No.: **29/868,016**

(22) Filed: **Nov. 16, 2022**

(51) **LOC (14) Cl.** **14-04**

(52) **U.S. Cl.**

USPC **D14/485**

(58) **Field of Classification Search**

USPC **D14/485-495**

(57) **CLAIM**

The ornamental design for a display screen with graphical user interface as shown and described.

DESCRIPTION

The FIGURE is a front view of an image for a display screen with graphical user interface showing our new design. The peripheral dash-dot-dash lines illustrate a display screen or portion thereof and form no part of the claimed design. The broken lines illustrate features that form no part of the claimed design.
